UNITED STATES PATENT OFFICE.

FREDERICK WILFRID SCOTT STOKES, OF WESTMINSTER, ENGLAND.

FREE ROLLER-SLUICE.

No. 825,944.

Specification of Letters Patent.

Patented July 17, 1906.

Application filed April 13, 1906. Serial No. 311,522.

To all whom it may concern:

Be it known that I, FREDERICK WILFRID SCOTT STOKES, civil engineer, a subject of the King of Great Britain, residing at 32 Victoria street, Westminster, in the county of London, England, have invented certain new and useful Improvements in Free Roller-Sluices, of which the following is a specification.

10 In free roller-sluices in which the roller-frame is suspended in the loop or bight of a rope or chain, one end of which is secured to a fixed support and the other end to the gate itself, the roller-frame travels upward at one-half the speed of the sluice, and consequently the rollers are left behind and subjected to the rush of water past them. To minimize this difficulty and also to allow of access to the parts for cleaning or repairs where the 15 lift of the sluice is greater than the range of lift against pressure, I arrange so that the rollers and sluice are lifted at the same relative speed at the point at which the rollers are no longer required.

20 In order that my said invention may be clearly understood and readily carried into effect, it will now be described more fully with reference to the accompanying drawings, in which—

25 Figure 1 is an end view of a sluice-gate embodying the features of my invention; and Fig. 2 is a similar view, part broken away, showing the position of the parts when the gate has been partly raised and at the moment when the pick-up device comes into 30 operation.

The same letters of reference where they occur are used to denote the same or corresponding parts in both figures.

35 In the drawings, A indicates the sluice-gate; B B, the rollers; D, the masonry, and E is the pick-up device or attachment herein-after referred to.

The roller-frame is suspended in the usual manner in the bight of a chain or rope a, passing round a pulley a⁶ on the roller-frame, one end of said chain or rope being fixed to the gate at a⁵. In order to carry out my invention, I fix the other end a⁴ of the chain or 45 rope a⁷ to a rod E² or its equivalent resting

on a bracket or brackets or other support E' in the masonry, and I provide the gate with a pick-up attachment E in the path of the rod E², which attachment lifts the said rod E², and with it the end of the chain or rope a⁷, 55 carrying the roller-train. From the time the rod E² is lifted the roller-frame and the rollers will travel upward at the same speed as the gate and will therefore be carried up clear of flood-level, or in the case of sluices 60 in dams or the like, above the water-level, so as to be readily accessible for cleaning, painting, or repairs. On lowering the sluice again the end or ends of the rod E² lodge on the former support or supports E', and 65 the rollers thereupon resume their original relative motion to the sluice at the required spot.

It is obvious that the pick-up arrangement herein described is applicable to any 70 free-roller-sluice system having its rollers secured in a suspended frame.

Having fully described my invention, what I claim, and desire to secure by Letters Patent, is—

75 1. In a free roller-sluice having its rollers secured in a suspended frame, the pick-up device in which the ropes or chains whereby the roller-frame is suspended have one end fixed to the gate and the other end secured 80 to a support which is so mounted and disposed within the path of the gate as to be taken up thereby when said gate has reached a point at which the rollers are no longer required for the purpose of resisting the pressure, substantially as and for the purpose 85 specified.

2. In a free roller-sluice having its rollers secured in a suspended frame, a pick-up device constructed, arranged and adapted to 90 operate substantially as hereinbefore described and for the purpose specified.

In testimony whereof I have hereunto set my hand, in presence of two subscribing witnesses, this 30th day of March, 1906.

FREDERICK WILFRID SCOTT STOKES.
